(57) **CLAIM**

The ornamental design for a postage and shipping label printing device with integrated scale as shown and described.

DESCRIPTION

FIG. 1 is a top, front and right side perspective view of a postage and shipping label printing device with integrated scale according to the present invention; FIG. 2 is a top, back and left side perspective view thereof;

FIG. 3 is a front view thereof;

FIG. 4 is a top view thereof;

FIG. 5 is a right side view thereof;

FIG. 6 is a left side view thereof;

FIG. 7 is a rear view thereof; and,

FIG. 8 is a bottom view thereof.

The broken lines immediately adjacent to the shaded areas depict the bounds of the claimed design, while all other broken lines, including those superimposed over shaded surfaces, are directed to environment. The broken lines form no part of the claimed design.

1 Claim, 8 Drawing Sheets
